UNITED STATES PATENT OFFICE.

LOUIS N. AMANS, OF ALBERTON, MONTANA.

DEVICE FOR TIGHTENING WIRE CABLES.

1,372,792.

Specification of Letters Patent. Patented Mar. 29, 1921.

Application filed March 23, 1920. Serial No. 368,106.

To all whom it may concern:

Be it known that I, LOUIS N. AMANS, a citizen of the United States, residing at Alberton, in the county of Mineral and State of Montana, have invented a new and useful Device for Tightening Wire Cables, of which the following is a specification.

It is the object of my invention to provide a novel wire stretcher which is easily attached, economical to manufacture, and which will stand the strain of tightening a cable and at the same time allow the cable to twist and turn. I attain these and other objects of my invention by the device illustrated in the accompanying drawings, in which—

Figure 1 is a side elevation of the invention;

Fig. 2 is a section on line 2—2 of Fig. 1; and

Fig. 3 is a section on line 3—3 of Fig. 1. Like numerals designate like parts in each of the views.

Referring to the accompanying drawings, I provide handles or frames 1 and 2, connected by pivot 3. Members 1 and 2 are provided with openings 4 at their ends, by which they are attached to links 5, which in turn are attached to link 6, to which is attached a swivel hook 7. Detachably mounted on the other ends of members 1 and 2 I provide blocks 8, which may be of any suitable size adapted for use with cables of different sizes, and secured to members 1 and 2 by suitable fastening pins or rivets 9. Blocks 8 are provided with tapering or wedge shaped sockets 11 extending longi-

tudinally of the face of the blocks. The sockets 11 are narrowest at the outer ends of the blocks, as illustrated in Fig. 2. 40 Mounted in the tapering sockets 11 are wedge shaped jaw members 10, shaped to fit snugly in sockets 11 and having a series of suitable teeth 12 extending longitudinally of their faces to engage the wire cable A in 45 the manner illustrated in Fig. 1. The sides 13 of the wedge shaped jaws 10 are of dovetail shape, as shown in Fig. 3, to prevent the jaws from working loose or dropping out. In consequence of the peculiar shape 50 of the wedge shaped jaws 10 and the manner of mounting them in blocks 8, they will engage more tightly in the blocks the harder the wire cable is pulled. By providing the swivel 7 connected with the links that are 55 attached to the ends of the handles or frames 1 and 2, the cable is permitted to twist and turn without turning the jaws or blocks. The construction of the device is such as to make it economical to manufacture and it is easily applied in stretching trolley wires and cables.

What I claim is:

In a device of the class described, the combination of crossed pivotally connected 65 frames, blocks pivotally mounted on the operating ends of the frames, said blocks having forwardly tapered sockets, said sockets being dovetail shape in cross section, and correspondingly shaped cable engaging 70 jaws detachably mounted in the sockets of said blocks.

LOUIS N. AMANS.
